UNITED STATES PATENT OFFICE.

ALBERT WESLEY BENJAMIN, OF YARKER, ONTARIO, CANADA.

FOLDING BOX.

1,368,100.

Specification of Letters Patent.

Patented Feb. 8, 1921.

Application filed January 27, 1920. Serial No. 354,346.

To all whom it may concern:

Be it known that I, ALBERT WESLEY BENJAMIN, a subject of the King of Great Britain, and resident of Yarker, in the Province of Ontario, Dominion of Canada, have invented certain new and useful Improvements in Folding Boxes, of which the following is a specification.

This invention relates to improvements in folding boxes, and the objects of the invention are to provide a simple and strong form of box adapted to withstand hard usage, of light construction, which may be folded into small space for return shipment.

Further objects are to protect the box when folded, and particularly with hinges and joints thereof so that they will not be injured by rough usage during the return shipment.

Further objects are to generally improve and simplify the construction of the box or container to better adapt the various parts to perform the functions required of them.

In the drawings:

Figure 1 is a perspective view of one embodiment of the invention.

Fig. 2 is a longitudinal sectional view.

Fig. 3 is a perspective view of the box when folded.

Fig. 4 is a longitudinal sectional view when folded.

Fig. 5 is a cross sectional view when folded.

Fig. 6 is a cross sectional view in normal position.

Fig. 7 is a perspective view of the corner lock, with the corners connecting.

Fig. 8 is a perspective view of the corner lock, with the corners separated.

Fig. 9 is a perspective view of the bottom corner.

Fig. 10 is a perspective detail of a corner of one of the hinged sides.

In the drawings, like characters of reference indicate corresponding parts in all the figures.

Referring to the drawings, A represents the bottom of the box, B the top, and C, D, E and F the four sides, hinged to the bottom and adapted to fold inwardly over each other, as shown in Figs. 4 and 5.

Each of these sides is conveniently constructed from a rectangular frame 10 filled in with wire bound slate 11 of any usual construction.

The sides are hinged at different distances above the bottom so that they will lie flatly,

one above the other. This is accomplished by hinging the sides to cross bars or strips 12 of different heights, and which are secured to the inside of the box. 60

In accordance with the present invention a protecting member G is provided around the exterior of the lower hinges of the sides, this member being in the form of a strip of wood or metal secured to the base and projecting upwardly a distance, being formed with four sides 13 connected by suitable corner braces 14. 65

The cover B is hinged to the side E, the hinge being preferably of the detachable type, conveniently formed for instance by a hook member 15 on the cover engaging on the member 16 on the side. 70

Corresponding eye members 17 are provided on the main protecting member G, so 75 that when the box is collapsed a hook member 15 on the cover may be engaged with the eye 17, forming a cover to the protecting member G, whereby the protecting member will constitute an inclosing casing or 80 container for the collapsed parts of the box, and protect them during shipment, the cover being retained on by a suitable hasp 18, which may engage a pivoted locking pin 19 on the protecting member, a corresponding locking pin 20 being provided on the side F 85 of the box.

Suitable locking means are provided for holding the corners of the folding sides together when in upright position, the details 90 of which locking means are shown in Figs. 7 and 8. They include an eye member 21 secured to one corner, the said corner having a catch 22 formed therein, which constitutes part of the eye, the member 21 being of an angle shape. 95

A hook member 23 is secured to the opposite corner adapted to engage the eye member, and a pivoted abutment member 24 adapted to be swung upwardly, and when so 100 swung to prevent disengagement of the hook member from the eye member.

Each of the sides C, D, E and F are pivoted by any suitable pivoting pins adapted to enter socket plate 25 on the extremities 105 of the sides.

From the foregoing description it will be seen that when collapsed, the folded sides and the hinges are effectively protected by the cover, which together with the protecting member constitutes an inclosing casing 110 for the hinged and pivoted sides. The box

when folded may thus be shipped in small space at low cost without danger of breakage.

As many changes could be made in the above construction, and many apparently widely different embodiments of my invention, within the scope of the claims, constructed without departing from the spirit or scope thereof, it is intended that all matter contained in the accompanying specification and drawings, shall be interpreted as illustrative, and not in a limiting sense.

What I claim as my invention is: —

1. A folding box comprising hinged sides, a bottom and detachable hinged top, a base, a protecting casing member extending for a distance from the base upwardly around the sides, eye members 17 on the upper edge of the rear wall of the box, eye members 17 on the upper edge of the rear wall of the protecting casing member, and hinge hook

members 15 on the box designed to engage with the eye members 17.

2. A folding box comprising hinged sides, a bottom and detachable top, a base, a protecting casing member extending a distance from the base around the sides, the top being designed to be hinged to the sides and close the box when assembled, the said top being bodily removed and designed to engage with the protecting casing to close the same when the box is collapsed, eye members on one of the folding sides of the box, and hook members on the opposite side of the box, and a pivotal abutment member adapted to hold the hook member in the eye member.

In witness whereof I have hereunto set my hand in the presence of a witness:

ALBERT WESLEY BENJAMIN.

Witness:

RUSSELL B. SMART.
